BUFFING MACHINE

Oliver W. Mojonnier, River Forest, Ill., assignor
to Mojonnier Bros. Co., a corporation of Illinois

Application March 15, 1946, Serial No. 654,623

17 Claims. (Cl. 51—50)

1

The present invention relates to buffing or polishing machines generally, and more particularly to machines which buff or polish the surfaces of tanks or vats, the term "tanks" being used generically herein to include both tanks and vats.

One object of the invention is to provide a buffing machine capable of buffing the exterior surfaces of tanks in an upright position.

Another object is to provide a novel turntable for supporting the tanks and tank parts to be buffed.

Another object is to provide a novel drive by which the turntable of the machine is rotated.

Another object is to make the several parts detachable, so that they may be removed and the machine left in readiness for use upon horizontal tanks, that is, tanks having their main axes horizontal instead of vertical.

These and other objects and features of the invention will be best understood upon reference to the following detailed description taken in connection with the accompanying drawings, in which I have shown a preferred embodiment of the invention.

The present invention is a companion to that illustrated in my prior application, Serial No. 611,545, filed August 20, 1945.

In said drawings,

Fig. 1 is a perspective view of a buffing machine constructed and arranged in accordance with the present invention, the turntable being removed;

Fig. 2 is a plan view of the same showing an upright tank in position for buffing its exterior, the central portion of the figure being broken away to bring the whole within the confines of the drawing;

Fig. 3 is a plan view of the turntable and its movable support;

Fig. 4 is a sectional detail through one of the shoes with which the turntable is provided, together with a portion of a tank and one of its feet, the plane of section being indicated by the line 4—4 of Fig. 3;

Fig. 5 is a plan view of the movable turntable supporting structure with the turntable removed, the plane of view being indicated by the line 5—5 of Fig. 7, and the position of the turntable when present being indicated by the dot and dash circle;

Fig. 6 is a substantially central longitudinal section of the movable frame, with a tank in place for buffing, the plane of section being indicated generally by the line 6—6 of Fig. 5;

2

Fig. 7 is a vertical transverse section, the plane of section being indicated by the line 7—7 of Fig. 2;

5 Figs. 8, 9 and 10 are detail views illustrating the turntable supports, Fig. 8 showing the main auxiliary frame in plan, Fig. 9 showing in elevation one of the ancillary supporting members, and Fig. 10 showing the details of a connection pin located on the main frame;

10 Fig. 11 is a transverse section illustrating the raising and lowering mechanism, the plane of section being indicated by the line 11—11 of Fig. 2;

Fig. 12 is a perspective view of a screw engaging 15 nut of the raising and lowering mechanism, showing the fins for retaining the nut in non-rotating position;

Fig. 13 is a similar view of the upper end of the 20 supporting member for the screw showing the slots into which the fins fit;

Fig. 14 is an elevation of the detachable friction drive for the turntable; and

Fig. 15 is a similar elevation view in a direction at right angles to that of Fig. 14.

25 Like characters refer to like parts throughout the several views.

The novel buffing machine comprises, in brief, a shiftable cradle or main frame A, an auxiliary frame B removably secured thereto, ancillary 30 supporting members B', a turntable C upon which the work to be buffed is located, a buffing head D having a positively driven buffing wheel, and suitable raising and lowering mechanism E by which the head B may be adjusted. The work in the 35 present instance consists of a tank T, the exterior of which is to be buffed. The main and auxiliary frames are shifted about as a unit over the floor of the shop where the machine is employed. The auxiliary frame B, the ancillary supporting members B' and the turntable C and its driving mechanism may be detached from the main frame and the machine may then be used upon other tanks and in different ways than herein disclosed, as pointed out in my prior application, Serial No. 45 611,545.

The main frame or cradle A is the same as is shown in said prior application and comprises two sides 20 and two ends 21, preferably channels welded together, the ends 21 resting upon the 50 sides 20. At an intermediate point, the sides are connected by suitable angle irons 22, welded to the bottom flanges of the sides. These constitute the supports for the traction motor 23 and the motor 24 which drives the turntable C.

55 It may be pointed out that the motor 23 drives

the wheels 25 and 26 when the machine is used to polish horizontal tanks in the way pointed out in my prior application. When it is used as contemplated by the present invention, it drives the turntable C. The wheels 25 and 26 are idle elements insofar as the present invention is concerned, and further reference to them will be avoided, except to point out that the two driving sprocket chains, designated *a* and *b*, are shown idle in Fig. 1, being strung over the shafts upon which the wheels 25 and 26 are mounted. The sprocket wheels *c* and *d*, with which they would cooperate, if used, are also shown in the same figure; they perform no function insofar as the present invention is concerned.

Passing now to a further consideration of the structure, essential to the present invention, it will be noted that the motor 23 rests upon a base plate carried by the angle bars 22. The motor 24 is mounted on two supporting frames 27 carried by the same cross bars 22.

On the under side of the frame A and near its ends, are bearings 28, secured to the under sides 20, in which are journaled two shafts 29, carrying traction wheels 30 which travel upon the floor. Upon each shaft 29, is secured a sprocket wheel 31. Sprocket chains 32 engage these wheels and drive them through the sprocket wheels 33 mounted on the shaft of the gear reducer 34, associated with the traction motor 23. The motor is reversible and hence the wheels 30 may be driven either way, to shift the frame A. The motor 23 is an electric motor and is controlled through a cable 35 running from the motor to the face of the switchboard 36, where suitable control devices are provided. When once set laterally, the main frame and associated parts may be moved to and fro upon the floor to vary the position of the work. The switchboard 36 includes a plate of metal with the various control devices (not shown) attached thereto.

The auxiliary frame B comprises a main arcuate member 37 provided with top and bottom flanges and end sleeves 38, by which it is removably attached to the adjacent end member 21 of the main frame A. For this purpose, the end member is provided at each of its ends with an upright pin 39 secured to a lateral projecting member 40, in the manner shown in Fig. 10, the various parts being welded together. When the frame member 37 is about to be positioned upon the pins 39, it is raised and the sleeves 38 are brought into line with the pins and then the frame is lowered. The arcuate member 37 is additionally supported by three legs. One of these, designated 41, is secured at its upper end to the inside of the member, preferably by welding. At its lower end, it carries a wheel 42 which rests upon the floor. The two other legs, designated 43, are secured, also preferably by welding, toward their upper ends, to the outside of the member 37, and are provided with wheels 44 at their lower ends. At their upper ends, the legs 43 receive the telescopic posts 48 which slip down within the same. The upper ends of the posts 48 terminate in bearing wheels 45 which are adapted to bear against the under side of the turntable C. These are double wheels to increase the bearing area which supports not only the turntable, but also the tank or other work upon it. The post 48 also passes down through a tube 49 which has a given length depending upon the tilt to be given the turntable. This tube 49 acts as a spacer upon the upper end of the post 48 by

fitting loosely upon it and serving to determine the distance it will pass into the leg 43. These spacing tubes 49 may be varied in length as desired. The upper end of each tube 49 bears against the underside of the yoke 50 and its lower end against the upper end of the corresponding leg 43. The post 48 will be held in place by suitable set screws 50a.

Diagonal braces 46 join the posts or legs 41 and 43 with the arcuate member 37. A transverse brace 47 joins opposite sides of the arcuate member.

The central pivot 51 of the turntable C is secured within a sleeve 52, welded to and forming part of a base plate 53. The plate is welded to flanges of the end member 21. The pivot is held against rotation when in set position by a set screw 56 passing through the sleeve 52.

The ancillary supporting members B' take the form of supporting posts 58 mounted upon supporting legs 59. The legs 59 terminate at their lower ends in anti-friction wheels 60 and the posts 58 terminate at their upper ends in similar wheels 61. The former engage the floor, and the latter engage the under side of the turntable. Each of the legs 59 is carried at the outer end of a horizontal arm 62 which passes through a wide sleeve or strap 63 which is welded at its ends to the adjacent member 21 of the frame A. The straps 63 lie on the side of the member 21 away from the auxiliary frame B. By means of bolts 64 passing through the sleeves 63, the arms 62 are held in laterally adjusted position. The telescopically mounted posts 58 extend down into the hollow legs 59. Before being slipped into the end of a leg, each post 58 is first passed through a tube 65 which serves as a spacer between the yoke 66, which carries the wheel 61, and the upper end of the leg 59. Each spacer 65 gives the associated upper wheel 61 its setting. It is held in place by the set screws 67. By giving the spacers 65 a proper length, the wheels 61 are properly set to engage the underside of the turntable C. The spacers 65, the same as the spacers 49 of the legs 43, may be varied in length. By completely filling up the space between the yoke and the upper end of the leg, they carry much of the weight imposed by the work upon the turntable.

The upper end of the pivot 51 bears within a socket 68 formed on the underside of the turntable C at its center. The turntable comprises, beside the socket member 68, a circular plate 69, provided with a downwardly extending peripheral flange 70. The plate 69 fits loosely upon the pivot 51 so that the same may be tilted about three or four degrees from the horizontal. This is accomplished by the initial setting of the anti-friction wheels and it may be varied by varying the length of the spacers 49 and 65.

The turntable plate 69 is rotated by friction wheels 73. These wheels, of which there is a pair, are mounted on a horizontal shaft 74, having a bearing 75 at one end, provided by a bracket 76, removably secured by bolts 71 to the same side of the frame end member 21 of the frame A as the sliding arms 62. At its opposite end, the shaft 74 rests in a bearing formed in the upper end of a triangular support 78. A truncated plate 77 lies adjacent to the plate 78. Between these plates 77 and 78, there are journaled two shafts 79, each of which carries anti-friction wheels 80 and 81. Two of these wheels bear against the outside of one of the wheels 73, and two against the companion wheel 73. Thus,

a sturdy bearing is provided for the friction wheels 13, 13, which engage the underside of the turntable near its periphery. The two supporting plates 17 and 18 terminate at their lower ends in elongations which are connected at their ends by a transverse member 12. The frame thus formed is secured preferably by welding to a base plate 86. The entire structure is removably secured by bolts 85 to the upper flanges of the side member 20, 20, of the frame A. A collar 83 upon the shaft 14 holds the friction wheels 13, 13, in place. The construction is such that the shaft 14 with its connected parts, which constitute the friction gearing unit, may be removed as a unit from the main frame A by removing the bolts 71 and 85. Due to the tilt of the turntable C downward toward the frame A, the weight of the work T upon that side of the table will be greater than upon the opposite side and hence there will be a better frictional bearing upon the friction wheels 13, 13. This tilting of the turntable is made for the purpose of providing increased friction at the driving point.

The end of the shaft 14, which extends beyond the bearing member 18, is provided with a sprocket wheel 87 which is keyed to the shaft. A sprocket chain 88, riding upon the wheel 87, drives it through the agency of the motor-driven sprocket wheel 89. The latter is located at the free end of the shaft of the speed reducer 90 of the work-driving motor 24. The motor 24 is a reversible motor so that it is possible to rotate the turntable C in either direction. This is of importance where the work contains connections which may constitute an obstruction to the continuous rotation. At this point it may be noted that the motor 24 is provided with a control cable 84 which runs to the switchboard and may be controlled by suitable mechanism thereon (not shown).

As clearly shown in Fig. 3, the upper face of the circular plate 69 of the turntable C is scribed by a plurality of concentric circles 91, which are used in centering the work upon the table. In placing a tank in position upon the turntable, the bottom 92 is preferably provided with interiorly threaded flanges 93 into which the upper ends of the feet 94 and 95 are screwed. When the same is ready for shipment, these temporary feet are replaced by permanent ones which are screwed into the same flanges 93, or otherwise secured as may be desired.

When the temporary feet 94, 95 are used, the shorter feet 94 are used with shoes 96, and the longer feet 95 are brought into direct contact with the table. It will suffice to describe one of the feet 94 and its shoe 96. When screwed at its upper end into the socket 93, its lower end is placed within its shoe 96, within its flange 97 which is not threaded as is the flange 93. The foot simply rests therein, and the flat portion of the shoe rests upon the face of the turntable plate 69. Each shoe is provided with an elongated central slot in which a retaining screw bolt 98 is located. This screw enters a threaded opening in the plate 69 and, by its head bearing down upon the upper surface adjacent to the slot, holds the shoe in place. Two shoes 96 are used. The feet 95, which are used without shoes 96, are a trifle longer than the feet 94. This difference is approximately the thickness of the sole of the shoe. The two feet 94 resting in their shoes 96 give the initial setting of the tank, and the remaining feet 95 are then unscrewed sufficiently to provide a good bearing upon the turntable

plate 69. In Fig. 3, the dotted lines 95' indicate the positions the legs 95 would occupy if they were shown in this figure.

Passing now to a description of the buffing wheel structure involving the head D, we have a horizontal support 100, in the form of a hollow shaft, upon the free end of which the head is mounted. The buffing wheel is positively driven by an electric motor 101, both wheel and motor being moved as a unit.

The horizontal support 100 terminates at its projecting end in a head plate 102, having a reduced portion or pintle 103. The head plate and pintle are adapted to receive a yoke 104 having a cross-piece 105 uniting two sides 106, 106. The cross-piece 105 is provided with a central bearing 107, adapted to engage the pintle 103 on the head plate 102. A ring 108 is fixed to the end of the pintle by any suitable device, as, for example, a set screw 109. The yoke 104 rotates upon the pintle 103. It may be fixed in different rotary positions by a series of bolts or pins 110 passing through cooperating holes in the head plate 102 into threaded openings in the yoke cross-piece 105. Upon loosening the pins, the yoke 104 may be rotated to any desired adjusted position and then the pins or bolts 110 reinserted and screwed home. Thus, an adjustment of the buffer head about the longitudinal axis of the supporting shaft 100 is provided.

Within the yoke 104 are plates 111 which combine with cross plates 112 and 112^a, to form an enclosing casing for the motor 101. This enclosure is preferably completed by straps 113^a welded at their ends to the side plate 111 and to the frame of the motor at their centers. The plates 111 have oppositely extending trunnions 113 which pass into bearings in the yoke members 106, 106. The enclosure for the motor 101 is held in different adjusted positions by means of one or more pins 114 passing through openings 114^a in one of the yoke plates 106 into tight engagement with corresponding holes in the motor frame plates 111, 111. These pins or bolts 114 are preferably threaded and pass into engagement with threaded openings in the frame member. The pins 114 may be varied in number and the holes 114^a, with which they cooperate, may be variously located, as desired. The same will be true of the pins 110 and their cooperating openings.

The motor 101, which drives the buffing wheel 115, is mounted on the free end of a buffer shaft 116, adapted to rotate in bearings 117, projecting from the cross plate 112 of the motor frame. A multiple belt 118 passes over grooved pulleys 119, 120, upon the motor shaft and the shaft 116, respectively. A fender 121 projects from the adjacent end of the motor frame member 112, out over the wheel 115, as a protective measure.

The motor 101 is an electric motor and is provided with a supply cable 122, having slack sufficient to care for it in its different positions and leading off to the far side of the switchboard 36, as the parts are viewed in Fig. 1, where it is supplied with suitable starting and stopping devices (not shown).

Coming now to the raising and lowering mechanism E, by which the horizontal support 100 is firmly supported with its free end bearing the head D, it will be noted that there are two upright posts 123, 123, seated down in the ground to a depth of several feet, depending upon the height to which the head is to be raised. The ground may be a concrete floor or other sub-

stantial structure capable of withstanding the strain of the machine.

These posts 123, 123, serve as the basic supporting members. Within them there are two telescopic members 124 which support the horizontal member 100. All these members are preferably hollow, the member 100 for lightness, the others to receive the screws 125. The upper ends of the posts 124 are cut to fit against the underside of the horizontal member 100 and are securely welded thereto. On the upper side of the member 100, are saddles 126, which are firmly secured at their ends by machine screws 127.

A thrust bearing 128 is secured, by welding, to each saddle 126, and the associated portion of the horizontal member 100. It extends above and below the saddle 126, as shown. It will suffice to describe one.

The screw 125 is journaled for rotation within the bearing 128, and is held in position by an upper collar 130 and a lower collar 131. These collars are pinned to the shaft so as to rotate with it. At a point well down within the post 123, is a nut 132 which is supported on a fixed hollow post 133 and held against rotation by lateral fins 134, entering slots 135 in the post 133. The screw 125 is threaded into the non-rotating nut. Hence, as the screw 125 is rotated, it will move up or down in the nut 132, according to the direction of rotation. At the bottom, the posts 123 and 133 are closed with a stop-plate 136 welded to the ends.

By rotating the screws 125 equal amounts in one direction, the support 100 is raised; and by rotating the same equal amounts in the opposite direction, it is lowered. To bring about these equal rotations, I employ a reversible electric motor 137. This motor moves up and down with the horizontal support 100 to which it is attached by a base 138, welded thereto along its lower edge, and tied at their upper ends by straps 139, 139, connected to the gearing support 140, which is secured to the other side of the horizontal support 100 with intervening blocks 141. The gearing support 140 carries a suitably journaled shaft 142 which projects through an opening 149 in the support 140. The shaft 142 is driven from the motor 137 through gearing, including a small sprocket wheel 143 on the motor shaft, a large sprocket wheel 144 on the shaft 142, and an interconnecting sprocket chain 145. Other sprocket chains 146 extend from small sprocket wheels on the shaft 142 to sprocket wheels 147 secured to the upper ends of the screws 125. The motor 137 is a reversible electric motor and is supplied with current through an electric cable, a portion of which is shown and designated 148. It communicates with suitable starting and stopping control devices upon the face of the board 36. Thus, by means of the motor 137, it is possible to raise and lower the buffer head and hence the buffing wheel.

The switchboard 36 is supported on two channel uprights 151 in parallelism to the main posts 123. The same is held to the posts 123 by straps 152, 153, welded thereto at their ends. The telescoping tubular member 124 is provided in each instance with two hand-holes 154 through which access may be had to the collars 131 and adjacent parts within the post.

The cables 35, 84, 122, and 148, as before indicated, are provided with sufficient slack to allow for the several adjustments occasioned by the motors 23, 24, 101 and 137, respectively. These cables extend through suitable openings (not

shown) in the switchboard 36 and, as before stated, are connected with suitable control devices. By properly manipulating these control devices, the machine may be operated in the manner indicated.

The various parts are preferably metal so as to be welded together, although other means of connecting may be employed, if desired.

Obviously, the holes which cooperate with the setting pins 114 may be as numerous as required and may be located so as to hold the buffing wheel almost vertical or almost horizontal, or at any other angle.

Thus, the buffer head D may be positioned with its wheel extending downward, as shown, to work upon the exterior of a tank, or if the tank be of extra length, then the buffer wheel may be shifted to extend upward. It may then work upon the upper portion of the long tank. Other changes in position will also be obviously made. Thus, if buffing the outside of a conical surface, the head may be shifted to a position approaching the horizontal, or the vertical, as the case may be.

Although the term "tanks" has been used throughout the preceding description, yet it will be understood that the particular buffing machine, as herein disclosed, is used mainly to polish the outside of vertical tanks and tank portions which can be placed upon a turntable. The word "tanks" is used in a generic sense to include tanks, vats and the like. In certain industries, the term "tanks" is used to describe those receptacles used for cooling and storage, while in the same industries the term "vats" is applied to receptacles used in processing different substances.

The terms used herein, both in the specification and claims, are used in an instructive sense and not in any limiting sense. By the term "buffing," in its various forms, it is intended to include grinding, polishing, and the like.

It will be understood, too, that changes may be made in the specific matter herein disclosed and, accordingly, the terms of the appended claims are relied upon to cover all such alterations and modifications which rightly come within the spirit and scope of the invention.

I claim:

1. A buffing machine comprising a turntable for receiving the work to be buffed, a movable support for said turntable, friction gearing upon said movable support engaging the underside of said turntable near its periphery, a motor for driving said friction gearing, a horizontal support having a projecting end, a positively driven buffing wheel mounted on the projecting end of said support and operative to buff the rotating piece of work upon the turntable, and means for shifting said turntable support relative to said horizontal support and for raising and lowering the latter whereby the buffing wheel is caused to do its work of buffing.

2. A buffing machine comprising a turntable, a movable support for said turntable, means for positioning the work upon said turntable, friction gearing upon said movable support engaging the underside of said turntable near its periphery, a motor for driving said friction gearing, a horizontal support having a projecting end, a positively driven buffing wheel mounted on the projecting end of said support and operative to buff the rotating piece of work upon the turntable, and means for shifting said turntable support relative to said horizontal support and for raising and lowering the latter whereby the buffing wheel is caused to do its work of buffing.

3. A buffing machine comprising a turntable, a movable support for said turntable, means for positioning the work upon said turntable, said positioning means including a pair of shoes adjustably secured to said turntable and feet resting in said shoes and secured at their upper ends to the work, means mounted on said movable support for rotating said turntable, a horizontal support having a projecting end, a positively driven buffering wheel mounted on the projecting end of said support and operative to buff the rotating piece of work upon the turntable, and means for shifting said turntable support relative to said horizontal support and for raising and lowering the latter whereby the buffering wheel is caused to do its work of buffering.

4. A buffing machine comprising a turntable, a movable support for said turntable, means for positioning the work upon said turntable, said positioning means including a pair of shoes adjustably secured to said turntable and feet resting in said shoes and secured at their upper ends to the work, friction gearing upon said movable support engaging the underside of said turntable near its periphery, a motor for driving said friction gearing, a horizontal support having a projecting end, a positively driven buffering wheel mounted on the projecting end of said support and operative to buff the rotating piece of work upon the turntable, and means for shifting said turntable support relative to said horizontal support and for raising and lowering the latter whereby the buffering wheel is caused to do its work of buffering.

5. A buffing machine comprising a turntable; a movable support for said turntable; means for positioning the work upon said turntable by engagement therewith at four points, at two of said points there being shoes adjustably secured to said turntable and feet resting in said shoes and secured at their upper ends to said work, and at the two remaining points there being only feet resting directly upon said turntable and secured at their upper ends to the work; means mounted on said movable support for rotating said turntable; a horizontal support having a projecting end; a positively driven buffering wheel mounted on the projecting end of said support and operative to buff the rotating piece of work upon the turntable; and means for shifting said turntable support relative to said horizontal support and for raising and lowering the latter whereby the buffering wheel is caused to do its work of buffering.

6. A buffing machine comprising a turntable; a movable support for said turntable; means for positioning the work upon said turntable by engagement therewith at four points, at two of said points there being shoes adjustably secured to said turntable and feet resting in said shoes and secured at their upper ends to said work, and at the two remaining points there being only feet resting directly upon said turntable and secured at their upper ends to the work; friction gearing upon said movable support engaging the underside of said turntable near its periphery; a motor for driving said friction gearing; a horizontal support having a projecting end; a positively driven buffering wheel mounted on the projecting end of said support and operative to buff the rotating piece of work upon the turntable; and means for shifting said turntable support relative to said horizontal support and for raising and lowering the latter whereby the buffering wheel is caused to do its work of buffering.

7. A buffing machine comprising a turntable for

receiving the work to be buffed, a movable support for said turntable normally giving said turntable a slight tilt from the horizontal, friction gearing upon said movable support for engaging the underside of said turntable on its low side, a motor for driving said friction gearing, a horizontal support having a projecting end, a positively driven buffering wheel mounted on the projecting end of said horizontal support and operative to buff the rotating piece of work upon the turntable, and means for shifting said turntable support relative to said horizontal support and for raising and lowering the latter whereby the buffering wheel is caused to do its work of buffering.

8. A buffing machine comprising a turntable for receiving the work to be buffed, a movable support for said turntable normally giving said turntable a slight tilt from the horizontal, friction gearing upon said movable support for engaging the underside of said turntable on its low side, a motor for driving said friction gearing, means for securely positioning the work upon said tilted turntable, a horizontal support having a projecting end, a positively driven buffering wheel mounted on the projecting end of said horizontal support and operative to buff the rotating piece of work upon the turntable, and means for shifting said turntable support relative to said horizontal support and for raising and lowering the latter whereby the buffering wheel is caused to do its work of buffering.

9. A buffing machine comprising a turntable, a movable main frame, a movable auxiliary frame detachably secured to said main frame, a vertical pivot for said turntable, a supporting sleeve secured to the end of said main frame in which said pivot is adapted to rest, ancillary supporting members secured to opposite portions of the end member of the main frame and extending outwardly therefrom, anti-friction wheels carried by said auxiliary frame and said ancillary supporting members and adapted to bear against the underside of said turntable near its periphery, and means for buffering work carried by said turntable.

10. A buffing machine comprising a turntable, a movable main frame, a movable auxiliary frame detachably secured to said main frame, a vertical pivot for said turntable, a supporting sleeve secured to the end of said main frame in which said pivot is adapted to rest, ancillary supporting members secured to opposite portions of the end member of the main frame and extending outwardly therefrom, anti-friction wheels carried by said auxiliary frame and said ancillary supporting members and adapted to bear against the underside of said turntable near its periphery and set to give said turntable a slight tilt downward toward said main frame, a friction gearing unit engaging by its driving wheel with the underside of said turntable at its low point, said gearing unit being removably secured to said main frame, a motor for driving said friction gearing, and means for buffering work carried by said turntable.

11. A buffing machine comprising a turntable, a movable main frame, a movable auxiliary frame detachably secured to said main frame, a vertical pivot for said turntable, a supporting sleeve secured to the end of said main frame in which said pivot is adapted to rest, ancillary supporting members secured to opposite portions of the end member of the main frame and extending outwardly therefrom, anti-friction wheels carried by said auxiliary frame and said ancillary supporting members and adapted to bear against the underside of said turntable near its periphery and set

to give said turntable a slight tilt downward toward said main frame, a friction gearing unit engaging by its driving wheel with the underside of said turntable at its low point, said gearing unit being removably secured to said main frame, a motor for driving said friction gearing, means for securely positioning the work upon the turntable, and means for buffing the work upon the turntable.

12. A buffering machine comprising a turntable, a movable supporting main frame, auxiliary supporting means cooperating with said main frame to support said turntable with a slight tilt downward toward said main frame, said auxiliary supporting means being removably connected to said main frame, a driving motor permanently mounted on said main frame, a gearing unit removably mounted on said main frame at a point adjacent to the low side of said turntable and operative to drive the same from said motor, means for securely positioning the work upon the turntable, and means for buffing the positioned work.

13. A buffering machine comprising a turntable for receiving a piece of work to be buffed, a movable main frame, a movable auxiliary frame detachably secured to said main frame, a vertical pivot for said turntable, a supporting sleeve secured to the end of said main frame in which said pivot is adapted to rest, ancillary supporting members secured to opposite portions of the end member of the main frame and extending outward therefrom, anti-friction wheels carried by said auxiliary frame and said ancillary supporting members and adapted to bear against the underside of said turntable near its periphery and set to give said turntable a slight tilt downward toward said main frame, a friction gearing unit removably secured to said main frame, a motor for driving said friction gearing, means for securely positioning said tank upon said turntable, a horizontal support having a projecting end, a head plate secured to said end of said horizontal support, a yoke pivotally mounted on said head plate, a buffering wheel and driving motor therefor pivotally mounted on said yoke, means for adjusting said yoke relative to said head plate, means for adjusting said buffering wheel relative to said yoke, means for shifting said main frame and auxiliary frame as a unit, and means for raising and lowering said horizontal support to shift said buffering wheel and its driving motor up and down.

14. A buffering machine comprising a main frame, a turntable removably mounted on a vertical pivot, a longitudinal shaft mounted in said main frame, a motor for driving said shaft, a detachable frictional drive between said motor

and longitudinal shaft, an auxiliary frame detachably secured to said main frame, anti-friction wheels carried by said auxiliary frame and adapted to bear against the underside of said turntable near its periphery, and means for buffering the work carried by said turntable.

15. A buffering machine comprising a main frame, a turntable removably mounted on a vertical pivot, a longitudinal shaft mounted in said main frame, a motor for driving said shaft, a detachable frictional drive between said motor and longitudinal shaft, an auxiliary frame detachably secured to said main frame, ancillary supporting members secured to opposite portions of said main frame, anti-friction wheels carried by said auxiliary frame and by said ancillary supporting members and adapted to bear against the underside of said turntable near its periphery, and means for buffering the work carried by said turntable.

16. A buffering machine comprising a main frame, a turntable removably mounted on a vertical pivot, a longitudinal shaft mounted in said main frame, a motor for driving said shaft, a detachable frictional drive between said motor and longitudinal shaft, an auxiliary frame detachably secured to said main frame, and supported by floor engaging posts, anti-friction wheels carried by said auxiliary frame and adapted to bear against the underside of said turntable near its periphery, and means for buffering the work carried by said turntable.

17. A buffering machine comprising a main frame, a turntable removably mounted on a vertical pivot, a longitudinal shaft mounted in said main frame, a motor for driving said shaft, a detachable frictional drive between said motor and longitudinal shaft, an auxiliary frame detachably secured to said main frame and supported by floor engaging posts, ancillary supporting members secured to opposite portions of said main frame and likewise having floor engaging posts, anti-friction wheels carried by said auxiliary frame and by said ancillary supporting members and adapted to bear against the underside of said turntable near its periphery, and means for buffering the work carried by said turntable.
